BABY SHOE

Sam Spiro, Brooklyn, N. Y.

Application July 26, 1940, Serial No. 347,745

1 Claim. (Cl. 36—50)

This invention relates to a new and improved baby shoe.

An object of this invention is to provide an improved shoe construction designed particularly for babies wherein the shoe is so formed as to facilitate the placement of the shoe on the foot without undue bending of the foot.

Another object of this invention is to provide in a baby shoe a fairly pliable or flexible sole structure and a front and rear section secured to the sole structure, the rear section forming the quarter including a heel part and an upper, and the front section including a toe and vamp part and a tongue, with the front section free from the rear section, and with the front section at its rear underlapping the rear section when the shoe is in applied position.

A further object of this invention is to provide in a shoe of this type an improved lacing embodying the use of a pair of short laces and correlated means between the laces and the front section whereby the laces cannot be pulled out by the child.

A still further object of this invention is to provide a shoe of this type wherein the rear section is formed with an integral heel and upper and which is substantially stiff so as to form an ankle support.

A further object of this invention is to provide a shoe of this type in which the lacing extends through eyelets carried by the forward edges of the upper and in which the lacing also extends through the tongue so as to retain the tongue in position.

A further object of this invention is to provide a fairly pliable baby shoe which may readily bend between the several parts thereof, but which at the same time will retain its original shape.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

50 In the drawing:

Figure 1 is a detail side elevation of a baby shoe constructed according to an embodiment of this invention.

Figure 2 is a detail front elevation of the shoe 55 in partly opened position.

Figure 3 is a fragmentary sectional view taken on the line 3—3 of Figure 1.

Figure 4 is a fragmentary sectional view taken on the line 4—4 of Figure 1.

Figure 5 is a fragmentary sectional view taken 5 on the line 5—5 of Figure 1.

Figure 6 is a fragmentary sectional view taken on the line 6—6 of Figure 1.

Figure 7 is a fragmentary sectional view taken on the line 7—7 of Figure 2.

Figure 8 is a fragmentary sectional view of a modified form of lace structure.

Referring to the drawing, the numeral 10 designates an outsole which is formed of fairly pliable or flexible leather or other suitable material and the numeral 11 designates generally the vamp, while the numeral 12 designates generally the quarter of the shoe. The outsole 10 is formed with inturned marginal edge portions 14 which are adapted to be stitched to the vamp 20 11 by stitching 13. The lower edge of the vamp 11 is inturned as at 15 and the stitches 13 are adapted to extend only through the two inturned portions 14 and 15.

An insole 16 is disposed within the shoe structure, engaging on the inner surface of the outsole 10 and preferably the insole 16 is adhesively secured to the outsole 10. The marginal edge portions 17 of the insole 16 engage over the stitched inturned portions 14 and 15 so that 30 these inturned portions will not chafe a foot.

The vamp 11 includes a toe portion 18 which is formed with a pair of rearwardly extending and rearwardly tapering wings 19. The lower edges of the wings 19 form a continuation of 35 the toe portion 18 and the wings 19 at their lower edges are adapted to be stitched or otherwise secured to the outsole 10 after the manner shown in Figure 3. The upper edges of the wings 19 are formed at their rear with an upwardly extending convex edge portion 20 and a reversely curved intermediate part 21 merging with convex upper edge 22. A combined tongue and vamp extension generally designated at 23 is stitched by stitching 24 to the rear edge of the 45 vamp 11 and the upper edges of the wings 19.

The vamp extension 25 extends upwardly and rearwardly from the vamp 11 and merges with the tongue 26. The vamp 11 together with the wings 19 are formed of fairly stiff leather or 50 other suitable material whereas the vamp extension 25 and the tongue 26 are formed of two stitched pieces of fairly pliable or flexible leather so that when the shoe is in applied position, the vamp extension 25 may bend whereas the 55

vamp 11 will remain fairly rigid. This will hold the toe portion or vamp of the shoe in its original condition or shape for a greater period of time than where the vamp extension 25 is formed 5 of quite rigid material.

The quarter 12 is formed of a pair of members 27 and 28 which as shown in Figure 5 overlap each other at their rear edges and the overlapping rear edges of the two members 27 and 28 10 are stitched together as at 29. Each member 27 and 28 is formed of an outer flexible wall 30 and an inner flexible wall 31. The two walls 30 and 15 31 are stitched together about their marginal edges by stitching 32 so as to form a double-walled upper which will be fairly stiff so that it will serve as an ankle brace and support and so that the quarter 12 will be maintained in its original shape for a fairly long period of time and through fairly hard usage.

20 The quarter 12 is stitched as at 32 to the outsole 10, the manner of stitching the quarter 12 to the outsole 10 being similar to that structure shown in Figure 3. The quarter 12 at its lower forward edge is formed with an upwardly and 25 forwardly extending straight edge 33 which merges into a convex edge 34. The edge 34 merges with a reversely curved forward edge 35 which constitutes the forward edge of the quarter 12 where it extends upwardly from the vamp extension 25. Each side portion 27 and 28 has secured thereto a pair of eyelets 36, the eyelets being in the form of grommets or the like. If 30 desired, the quarter 12 at its lower rear portion may have secured thereto a heel stiffening element 37. This stiffening element may if desired be interposed between the two wall members 30 and 31.

The quarter 12 is unattached with respect to the vamp 11 and the vamp extension 25 and also 40 with respect to the tongue 26. The lower edge of each side-wall-forming member 27 and 28 extends forwardly at its forward portion beyond the rear end of a wing 19 so that each side wall forming member will overlap the rear end of a 45 wing as shown in Figure 1.

The quarter 12 is adapted to be held tightly or snugly on the foot by means of a pair of laces 38 and 39. The lace 38 is an upper lace and is threaded through the upper pair of eyelets 36 whereas the lace 39 is a lower lace and is threaded 50 through a lower eyelet 36. Preferably the tongue 26 has a pair of narrow slits 40 in the upper portion thereof through which the lace 38 is adapted to be threaded. The tongue 26 is also formed 55 with a second or lower pair of slits 41 through which the lace 39 is adapted to be threaded.

Each lace is preferably formed with an enlargement 42 which is formed by cutting a lace and overlapping the cut ends and then securing 60 the overlapping ends together by stitching 43 as

shown in Figure 7. The lace enlargement 42 is adapted to be disposed on the rear or underside of the tongue 26 between the slits so that when the laces are in applied position, that is, threaded through the slits 40 and 41 and the eyelets 36, 5 the laces 38 and 39 will be held against endwise movement. Through the medium of the enlargement 42, the tongue 26 will be held against twisting or rearward shifting between the open sides of the quarter 12 and in addition a small child 10 will not be able to pull the laces 38 and 39 completely out of the shoe.

By providing a shoe as hereinbefore described, the shoe may be placed on or removed from the foot by bending the sole as at 44. The outsole 10 15 together with the insole 16 form an integral hinge structure for hingedly connecting the quarter 12 onto the vamp 11. The quarter 12 may be bent downwardly as shown in dotted lines in Figure 1 so that the toe portion of the child's foot may be 20 inserted in the vamp 11 whereupon the quarter 12 may be raised and the laces 38 and 39 threaded through the eyelets 36. As shown in dotted lines in Figure 1, the rear edges 45 of the tongue 26 are substantially vertical when the shoe is in applied position. Through the use of a shoe as hereinbefore described, the shoe may be readily applied on or removed from the foot without unduly bending the foot so that this shoe will not cause a child to distort its foot during the time 30 that the shoe is being applied on or removed from the foot.

This shoe may be constructed without undue increase in the cost of the shoe and at the same time the shoe will retain its original attractive 35 appearance for a longer period of time than is possible with shoes of a different type not embodying the features of this invention.

In Figure 8 there is shown a slightly modified form of this invention wherein the tongue 26^a 40 has lacings 38^a extending through the slits 40^a. The lacings 38^a are formed of a single length of lacing, each lacing being folded double in substantially the center as at 42^a and the double folds stitched as at 43^a, so as to form an enlargement 45 which will not pass through the slits 40^a.

What I claim is:

In a shoe including a sole, a quarter and a vamp, said quarter overlying said vamp and free therefrom and having eyelets at its free edges, a 50 tongue carried by said vamp and underlying the quarter and free therefrom and having pairs of slits aligning with said eyelets, a lace engaging through a pair of eyelets in the quarter and a pair of slits in the tongue, and an enlargement 55 carried by said lace between a pair of slits and constituting a stop means to hold said lace against withdrawal.

SAM SPIRO. 60
